KNITTING NEEDLE

Ellen Williamson, Princeton, N. J., assignor to
Knitmark Inc., Princeton, N. J., a corporation
of New Jersey

Application November 23, 1948, Serial No. 149,797

Term of patent 3½ years

(Cl. D47—5)

To all whom it may concern:

Be it known that I, Ellen Williamson, a citizen of the United States, residing at Princeton, New Jersey, have invented a new, original and ornamental Design for a Knitting Needle, of which the following is a specification, reference being had to the accompanying drawing, forming part thereof.

In this showing:

Fig. 1 is an elevation on an enlarged scale of a knitting needle showing my new design, while

Fig. 2 is a plan view on the same scale of the needle, and

Fig. 3 is a perspective view of the head portion of the needle.

I claim:

The ornamental design for a knitting needle, as shown.

ELLEN WILLIAMSON.
